BY

A. Murphy Jr. ATTORNEY.

UNITED STATES PATENT OFFICE.

BERNARD NEVIN, OF TOLEDO, OHIO.

RATTLER.

1,380,303.

Specification of Letters Patent. Patented May 31, 1921.

Application filed June 18, 1920. Serial No. 389,992.

To all whom it may concern:

Be it known that I, BERNARD NEVIN, a subject of the King of Great Britain, residing at Toledo, in the county of Lucas and State 5 of Ohio, have invented certain new and useful Improvements in Rattlers; and I do hereby declare the following to be a full, clear, and exact description of the invention, such as will enable others skilled in the art 10 to which it appertains to make and use the same.

This invention relates to new and useful improvements in rattlers and more particularly to an amusement device and has for its 15 primary object the provision of a device adapted to be placed in an ordinary envelop and when removed therefrom to create a noise or rattle to startle or scare the person removing the same, thereby affording considerable amusement.

Another object of this invention is the provision of a card contained in a wrapper and which card has a noise producing element actuated by a wound elastic member 25 and adapted to strike the wrapper with considerable force when the device is removed from the envelop thereby creating a rattle or noise.

A further object of this invention is the provision of a rattler of the above stated character, which will be simple, durable and efficient, and which may be manufactured and sold at a comparatively low cost.

With these and other objects in view as 30 will become more apparent as the description proceeds, the invention consists in certain novel features of construction, combination and arrangement of parts as will be hereinafter more fully described and 35 claimed.

For a complete understanding of my invention, reference is to be had to the following description and accompanying drawings, in which:—

40 Figure 1 is a view illustrating a rattler constructed in accordance with my invention,

Fig. 2 is a sectional view illustrating the rattler within an envelop and its wrapper,

50 Fig. 3 is a sectional view illustrating the manner of connecting the sound producing element to the elastic element.

Referring in detail to the drawings, the numeral 1 indicates a card of a size to correctly fit within an envelop and is provided with a rectangular opening 2 and notches 3 in its edges. A rubber or elastic band 4 is

placed about the card 1 within the notches and extends across the opening 2. An elongated noise producing element 5 is positioned between the runs of the elastic band 4 within the opening 2 and is secured to the elastic band by strips 6 passing over the runs of the elastic band and secured to the noise producing element 5 at each side of 65 said band.

In operation, the noise producing element 5 is manually rotated until the band 4 is entirely twisted or wound and the card 1 is placed between a folded sheet of paper 70 or wrapper 6' and is then placed in an envelop 7 which holds the element 5 from unwinding and the envelop is sealed and given or mailed to a person who opens the envelop and withdraws the card 1 with the impression of receiving a missive or letter and the elastic band 4 rotates the sound producing element 5 rapidly against the wrapper when the card 1 is withdrawn from the envelop creating a noise or sound which resembles 80 the sound of a snake thus scaring the person and thereby rendering considerable amusement.

While I have shown and described the preferred embodiment of my invention, it 85 will be understood that minor changes in construction, combination, and arrangement of parts may be made without departing from the spirit and scope of the invention as claimed.

Having thus described my invention what I claim is:—

A rattler comprising a card having an opening and notches in its edges, an elastic band fitting in said notches and extending 95 across said opening, a sound producing element positioned between the runs of the band within the opening, strips secured to said sound producing element and overlying the runs of the band, said sound producing element adapted to be manually rotated until the band is fully twisted, a wrapper 100 about the card and said element and adapted to be positioned in an envelop along with the card, said sound producing device adapted to be rapidly rotated against the wrapper by the band unwinding when the card is removed from the envelop to create a sound.

In testimony whereof I affix my signature in presence of two witnesses.

BERNARD NEVIN.

Witnesses:

BERNARD BLANK,
THOS. A. GRAY.
